UNITED STATES PATENT OFFICE.

JAMES M. BISING, OF JERSEY CITY, NEW JERSEY, ASSIGNOR TO AMERICAN ROAD MACHINERY COMPANY, INC., OF KENNETT SQUARE, PENNSYLVANIA, A CORPORATION OF DELAWARE.

SNOWPLOW.

Application filed April 23, 1926. Serial No. 104,013.

My invention relates to snow plows and more particularly to that type of snow plow which is adapted for attachment to motor trucks, tractors or other convenient sources 5 of power.

Plows of the character to which my invention pertains are of great value in opening and maintaining open highways and in connection with the removal of snow from city 10 streets, their value being particularly derived from the fact that they may be readily attached to, and detached from, an otherwise useful source of power and, perhaps equally, from the fact that they may be operated at 15 relatively high speed.

Such plows are usually of the blade type and are so constructed as to readily pass over obstructions without injury to the blade, thus enabling them to be operated rapidly and 20 without particular attention to the existence of obstructions, such for example, as man-hole covers and the like. The capacity for passing over obstructions possessed by plows of the character referred to, is dependent upon 25 the mounting of the blade on a longitudinal axis and the provision of tension means tending to hold the blade in a working position, governed by a stop. When an obstruction is met, the blade may tilt forwardly on its axis, 30 against the action of the tension means with the result that its working edge is moved backwardly and upwardly and is enabled to pass over the obstruction. The blade is then returned to working position by the tension 35 means.

Plows of the character to which my invention pertains, while usually of the blade type, are not infrequently of the V type, but such plows when of the V type have no capacity to 40 yield for passing over obstructions, it being usual to depend on runners for guiding the plow bodily over any obstructions met with.

The plows of both the blade and V type are 45 open to various objections chief among which are that the blade plows, having the capacity to yield and avoid damage to themselves on meeting with obstructions, are inefficient due to the tilting of the blade which throws the entire blade out of operation or working position and snow is permitted to pass over and

under it. The V type plows, having no capacity to yield on meeting an obstruction, are subject to serious damage, unless operated slowly and with the greatest care, or so adjusted as to be clear of any possible obstruction. Either method of avoiding obstructions results in inefficiency. 55

Now it is the object of my invention to provide a snow plow which will retain all the advantages of the present plows of the character indicated and at the same time, will be so constructed as to adapt itself to obstructions without injury therefrom and to have increased efficiency due to superior plowing action. 65

More particularly my invention contemplates the provision of a plow having two parts, one an adjustable working blade mounted rigidly above the road surface and the other a yieldingly mounted cutting edge positioned 70 to the rear of and below the working blade. 65

My invention, while primarily adaptable to snow plows of the blade type, is fully adaptable to V type plows.

Having now indicated, in a general way, 75 the nature and purpose of my invention, I will proceed to a detailed description thereof with reference to the accompanying drawings in which there is illustrated a preferred embodiment and in which:—

Fig. 1, is a side view of a snow plow embodying my invention, illustrated as attached to a motor truck or tractor, indicated diagrammatically.

Fig. 2, is a plan view of the plow illustrated in Fig. 1. 85

Fig. 3, is a front view of the subject of Fig. 1.

In the several figures *a* indicates a motor truck or tractor, having a front axle *b* to 90 which are clamped brackets *c* to which are pivotally connected the rear ends of the side members of a frame *d*.

Upon the frame *d* is mounted a semicircle *e*, suitably braced by members *f* and pivotally 95 secured to the forward end of the frame by a pivot pin *g*. The semicircle is rotatable relative to the frame about the pin *g* and is adapted to be positioned relative to the frame by means of a pin *h* which is passed through 100

a bracket *i*, which is supported on frame *d*, and through any one of a series of holes *j* in the semicircle. The pin *h* thus serves to secure the semicircle to the frame *d* through the medium of bracket *i*.

5 A pair of rollers, or other supporting device, *k* is positioned beneath opposite sides of the semicircle and is connected thereto through springs contained in casings *l* secured to the semicircle.

10 A blade *m*, of desired length and height is pivotally connected to the semicircle by means of pins *n*, which extend longitudinally of the blade and support the blade with its lower edge *m'* substantially spaced from the ground. The blade is retained in working position by means of blade stops, *o* and *p*, pivotally connected to the casings *l* and to the blade by a pin *t'*, and are also connected 15 to each other through the medium of turnbuckles or other adjustable device *q*. Thus it will be noted that the position of the blade about the pins *n* is fixed, but may be adjusted to various angular positions by manipulation of the turnbuckles *q*.

20 A second blade *r* of the same, or substantially the same, length and of a height in excess of the distance that the lower edge *m'* of the blade *m* is spaced from the ground, and having wing like extensions *r'* at its 25 ends, is secured to arms *s*, which are in turn pivotally secured to the blade *m*, or to any convenient support as the semicircle *e*, by means of pins *t*, which pass through angle members *u*, which serve to stiffen blade *m*, and through arms or levers *s*. The arms *s* are of such shape and length as to enable the 30 positioning of blade *r* a distance behind blade *m* and with its lower edge on or adjacent to the ground, so that the blade *r* will act in a 35 space equal to the space between the lower edge *m'* of blade *m* and the ground and not occupied by the blade *m*.

The blade *r* is yieldingly retained in position by means of springs *v*, one associated 40 with each of the arms or levers *s*.

The springs *v* are carried on reduced portions of rods *w* each pivotally secured at one end to the blade *m* by a pin *n'*. The reduced 45 portions of rods *w* pass through holes in arms *s* and bosses *x* on arms *s* and the springs are confined thereon, at a set tension, between the bosses *x* and washers retained by nuts *y* threaded on the rods.

50 Thus the springs act against the bosses *x* on arms *s* and tend to move the arms and blade *r* forwardly about the pivots *t*, the forward position of the blade being fixed by abutment of the arms *s* against the shoulders 55 formed on rods *w* by reducing the portion thereof passing through the arms and bosses *x*.

The plow and frame *d* with semicircle *e* is adapted to be lifted about the pivotal connection between the frame and brackets *c* on

the truck or tractor axle and for this purpose a hoisting device *2* is supported on a frame *3* mounted on the truck or tractor frame and suitably braced therefrom by chains *4*. The hoisting device is conveniently operated through a shaft *5* and is connected to the ends of the semicircle by means of chains *6* and *7* connected through a sheave *8*.

70 It will now be observed that by virtue of my invention, a snow plow is provided having a main and secondary blade, the main blade being retained in a fixed position on its longitudinal axis and having its lower edge spaced from the ground. The secondary blade being positioned behind the main blade and in operative relation with the ground, to act as a clean-up blade, and so mounted as to have the capacity for swinging backward and upward on a center above and ahead of it, in order to clear obstructions.

75 Thus it will be observed that by virtue of my invention, a snow plow is provided which under all circumstances, will retain a maximum efficiency, and especially on meeting 80 with an obstruction, since the main blade is constantly in operative position, thus preventing the passage of snow over it and the secondary blade has the capacity for independently adapting itself to obstructions 85 and, at the same time, since it handles but a small depth of snow under normal conditions, insuring maximum efficiency in the removal of snow.

90 Having now fully described my invention, what I claim and desire to protect by Letters 100 Patent is:—

1. A snow plow comprising a supporting frame, a main blade supported thereby, and a second blade in back of and extending below the main blade and pivotally supported with 105 relation to the main blade in front of the second blade.

2. A snow plow comprising a main blade, a second blade spaced from and extending below the main blade, means for pivotally supporting the second blade from the main blade in front of the second blade, and means acting to yieldingly retain said second blade 110 in working position.

3. A snow plow comprising a main blade, means to support the main blade in a fixed working position with its lower edge spaced from the ground, a second blade in back of and extending below the main blade, and means for pivotally supporting the second blade from the main blade in front of the second blade.

4. A snow plow comprising a main blade, means to support the main blade in a fixed working position with its lower edge spaced from the ground, a second blade in back of and extending below the main blade, means for pivotally supporting the second blade from the main blade in front of the second 125 130

blade, and means acting to yieldingly retain said second blade in working position.

5. A snow plow comprising a blade pivotally mounted on a longitudinal axis, adjustable means for retaining said blade in a fixed position, a second blade pivotally connected to said first mentioned blade between the two blades for supporting said second blade in a position spaced from said first blade, and 10 means for yieldingly retaining said second blade in working position.

6. A snow plow comprising a blade pivotally mounted on a longitudinal axis, adjustable means for retaining said blade in a fixed position, a second blade, means pivotally connected to said first mentioned blade for supporting said second blade in a position spaced from said first blade and means supported from said first blade and acting on said last 20 mentioned means for yieldingly retaining said blade in working position.

7. In a snow plow in combination with a frame adapted for attachment to a vehicle, a blade supported from said frame, a second 25 blade pivotally supported from said first blade in a position behind and in overlapping relation with said first blade, tension means supported from said first blade and acting on said second blade to move it forward and 30 means adapted to fix the forward position of said second blade.

8. In a snow plow in combination with a frame adapted for attachment to a vehicle, a blade supported from said frame, a second 35 blade pivotally supported from said first blade in a position behind and in overlapping relation with said first blade, tension means supported from said first blade and acting on said second blade to move it forward and a 40 stop supported from said first blade and adapted to fix the forward position of said second blade.

9. In a snow plow in combination with a frame adapted for attachment to a vehicle, a blade supported from said frame and having 45 its lower edge spaced from the ground, an arm pivotally secured to said first blade, a second blade secured to said arm in a position behind said first blade and extending below the lower 50 edge thereof, a rod pivotally attached to said first blade and having a reduced portion extending through and beyond said arm, a spring on said arm, and means engaging said rod and adapted to confine said spring 55 against said arm.

10. In a snow plow in combination with a frame adapted for attachment to a vehicle, a blade supported from said frame and having its lower edge spaced from the ground, an 60 arm pivotally secured to said first blade, a second blade secured to said arm in a position behind said first blade and extending below the lower edge thereof, a rod pivotally attached to said first blade and having a reduced portion extending through and beyond 65

said arm, a spring on said arm, and means engaging said rod and adapted to confine said spring between itself and one side of said rod and stop means adapted to contact with the other side of said arm.

11. In a snow plow in combination with a frame adapted for attachment to a vehicle, a blade supported from said frame and having its lower edge spaced from the ground, an arm pivotally secured to said first blade, a 70 second blade secured to said arm in a position behind said first blade and extending below the lower edge thereof, a spring supported from said first blade and adapted to act on said second blade to move it forward and a 75 stop fixing the forward position of said second blade.

12. In a snow plow in combination a frame adapted to be pivotally attached to a vehicle, a blade pivotally attached to said frame, adjustable means for fixing said blade in a working position with its lower edge spaced from the ground, a second blade pivotally supported from said first blade, means adapted to normally retain said second blade in a position behind said first blade and in overlapping relation thereto, said means being adapted to yield to permit said blade to move rearwardly and upwardly on striking an obstruction.

13. In a snow plow in combination, a frame adapted to be attached to a vehicle, a semicircle rotatably mounted on said frame, a blade pivotally attached to said semicircle, means for securing said blade in a fixed position relative to the semi circle and a second blade pivotally supported from said first blade.

14. In a snow plow in combination, a frame adapted to be attached to a vehicle, a semicircle rotatably mounted on said frame, a blade pivotally attached to said semicircle on an axis extending longitudinally of said blade, braces connected to said blade and semicircle adapted to fix the position of the blade relative to the semicircle, a second blade pivotally supported from said first blade, a stop adapted to fix the normal position of said second blade, and tension means adapted to yieldingly retain said blade in normal position.

15. In a snow plow in combination, a frame adapted to be attached to a vehicle, a semicircle rotatably mounted on said frame, a blade pivotally attached to said semicircle on an axis extending longitudinally of said blade, braces connected to said blade and semicircle, a means for affording an adjustable connection between said braces, an arm pivotally connected to said first blade, a second blade supported by said arm in a position behind said first blade, tension means supported from said first blade and yieldingly acting to move said second blade forwardly,

and a stop adapted to fix the forward position of said second blade.

16. A snow plow comprising a main blade, means to support the main blade in a fixed working position with its lower edge spaced 5 from the ground, a second blade in back of and extending below the main blade, and levers pivoted in front of said second blade for supporting said blade.

17. A snow plow having a supporting 10 frame, a main blade connected to the frame, a second blade in back of and extending below the main blade, supporting levers for the second blade, said levers extending upwardly and forwardly from the second blade, and 15 means for pivotally supporting the upper ends of the levers.

18. A snow plow having a supporting frame, a main blade connected to said frame including means for adjusting said blade, a second blade in back of and extending below the main blade, levers for supporting the second blade extending upwardly and forwardly thereof, and pivotally connected to 25 the first blade, and yielding means for the second blade pivotally carried by the main blade.

19. A snow plow having a supporting frame arranged to be pivotally attached to a vehicle, 30 casters for supporting the forward end of said frame, a main blade pivotally carried by said frame, means for adjusting said main blade, levers pivotally connected to the main blade at their upper ends, said levers extending 35 backwardly and downwardly from the main blade, a second blade in back of the main blade connected to the lower ends of said levers, and yielding means connected to the first and second blades for maintaining the 40 second blade in operative position.

20. A snow plow having a main frame adapted to be pivotally attached at its rear to a vehicle, a supplementary frame pivotally attached to the main frame at its forward 45 ends, a main blade adjustably connected to the supplementary frame, levers connected to the main blade at their upper ends and extended backwardly and downwardly from the pivotal points, a second blade connected to 50 the lower ends of said levers, said blade being in back of the main blade and extending below the lower edge thereof, caster wheels connected to the supplementary frame, and springs interposed between the main blade 55 and the second blade for holding the second blade in operative position.

21. A snow plow having a main frame adapted to be attached to a vehicle to swing about a horizontal axis, a supplementary 60 frame pivotally mounted on the forward end of the main frame and arranged to swing about a vertical axis, a main blade adjustably connected to the supplementary frame, casters for supporting the supplementary frame, 65 levers connected at their upper ends to the

main blade, said levers extending backwardly and downwardly from their pivotal connections, a second blade connected to the lower ends of said levers, said second blade being in back of the main blade and extending below the lower edge of the main blade, a plurality 70 of rods pivotally connected to the main blade and extending through openings in said levers, and springs mounted on said rods for retaining second blade in working position.

In testimony of which invention, I have 75 hereunto set my hand, at Kennett Square, Penna., on this 13th day of April, 1926.
